CLAIM

The ornamental design for a physiological nose sensor, as shown and described.

DESCRIPTION

FIG. 1 is a perspective view of an embodiment of a physiological nose sensor showing our new design; FIG. 2 is another perspective view thereof;

FIG. 3 is top view thereof;

FIG. 4 is bottom view thereof;

FIG. 5 is a side view thereof;

FIG. 6 is another side view thereof;

FIG. 7 is a front view thereof; and,

FIG. 8 is a back view thereof.

Broken lines, where shown, are used to illustrate portions of the physiological nose sensor that form no part of the claimed design.
